PICKET FENCE SECTION

Boardman M. Randall, Portsmouth, N. H.

Application April 1, 1947, Serial No. 738,676

2 Claims. (Cl. 256—24)

1

This invention relates to improvements in ramoso structural elements of sheet material and in methods of producing them economically from a sheet having predetermined dimensions. More particularly it relates to ramoso elements which may be fashioned economically from a sheet of plywood or other sheet material, and which easily and quickly may be assembled together and be staked to the ground to provide a straight picket fence of any desired length, or which may be assembled as a circular enclosure of any desired circumference around a flower bed or the like. The invention provides so that a stock size sheet of plywood will produce two fence sections and two fence rail sections, utilizing the entire initial sheet or panel with total avoidance of any waste. However, it should be understood that the ramoso elements produced according to the invention, in suitable sizes, may have any of a variety of other uses, such as in the manufacture of baby pens, as racks for numerous purposes, and as the head of a rake when one of the ramoso elements is suitably equipped with a handle.

It is among the objects of the invention to provide a method of producing ramoso structural elements having multiple integral uniformly dimensioned and spaced branches which may constitute pickets of a fence, supporting members of a rack, or teeth for a rake or the like, said elements being fashioned from a sheet or panel of plywood, for example, with complete utilization of the entire area of the sheet or panel.

Another object is to provide ramoso structural elements whose terminal portions are adapted to be butted and secured together to provide a fence or the like of any desired length and having uniform configuration from end to end of the fence.

A further object is to provide a method whereby two identical sections of picket fence and two identical fence rails may be cut from a panel of plywood of predetermined rectangular shape and size with complete utilization of the stock of the panel and with the end portions of the fence sections adapted to be butted together without interruption of the continuity and uniformity of the fence structure.

Yet another object is to provide plywood fence sections, each comprising multiple pickets integrally joined together along the base of the section and each having at least one stake pivotally secured to its base at an end of the section and adapted, when depending at right angles to the base, to project beyond the section for securing thereto of a next adjacent fence section.

It is, moreover, my general object and purpose

2

to provide an improved method and a ramoso structural product which have particular utility for the manufacture of sectional picket fences capable of quick and easy assembly and installation.

In the accompanying drawings:

Fig. 1 is a plan view of a stock size panel of plywood having dotted line indications thereon of the lines of cutting for producing two fence sections and two fence rails in accordance with the invention;

Fig. 2 is an elevational view showing three fence sections assembled in end to end relation with the fence rails and stakes mounted on the sections;

Fig. 3 is a top plan view of a fence assembled and installed in circular form; and

Fig. 4 illustrates how one of the ramoso sections, of suitable size, may be employed as the head of a rake.

Referring to the drawings, the blank 10 of Fig. 1 preferably will be a stock size panel of plywood which may be forty-eight inches long and twenty-four inches wide, for example. The number of plies and the over-all thickness of the plywood may be varied as desired, although I have found that a three-ply panel one-quarter of an inch thick adequately serves my purposes. The panel preferably should be of the sort recommended for exterior use which ordinarily will be specially treated during or subsequent to manufacture to withstand weather conditions.

According to the invention, the blank 10 is cut to provide two identical ramoso elements, each of which has multiple branches, or pickets or teeth integrally connected together along one edge of the element. When the ramoso elements are to constitute sections of a picket fence, two similar strips 12 preferably will be first cut from the blank 10, as along the dotted lines 13 and 14 in Fig. 1, to provide two identical fence rails. The strips 12 are cut lengthwise of the panel 10 so that, assuming a panel forty-eight inches by twenty-four inches, each strip will be forty-eight inches long. The width of the strips may be varied as desired but I prefer to make them one and one-half inches wide. This removes three inches from the width of panel 10 which, in the case of a twenty-four inches wide panel 10, leaves a panel twenty-one inches wide and forty-eight inches long, from which two fence sections are to be cut.

The fence sections may be cut along the continuous dotted line 16 by a band saw if desired. However, for economical mass production of the

fence sections, it is desirable to die-cut the panel on the dotted line 16 thereby to quickly and effectively produce two fence sections with each working stroke of the die.

As clearly evident in Fig. 1, the lower edge portion of panel 10 constitutes the base portion 18 of one fence section from which pickets 20 project integrally in spaced relation, and the upper edge portion of panel 10 constitutes a base portion 18 of another fence section from which pickets 20 project integrally in spaced relation. The intact base portions 18 may be three inches wide or deep, for example, so that each picket 20 will project fifteen inches from its base portion in the assumed case of a panel initially twenty-four inches wide reduced to twenty-one inches wide by removal of strips 12, 14. In such a case, there may be twelve pickets on each section each two inches wide and with two inch spacing of the pickets.

The complementary arrangement of the two fence sections in the panel 10 of Fig. 1 is such that one end of each section terminates in the plane of the outer edge of its end-most picket and the other end has its base portion 18 extending, as at 19, beyond its end-most picket to the plane of the outer edge of the end-most picket of the complementary section, so that the two fence sections produced from a panel 10 are in every respect identical with a base projection 19 adapted to be butted against the end of an adjacent section in the plane of the outer edge of the end-most picket of the adjacent section when the sections are associated together with their base portions 18 in alignment, each said butted projection 19 serving to properly space the end-most pickets of adjacent sections and providing continuity and uniformity of the fence structure from one section to another of a fence.

Referring more particularly to Fig. 2, one of the rail strips 12 is secured lengthwise of each fence section a suitable distance inward from the tips of pickets 20. However, one end of each rail 12 is positioned centrally of the width of an end-most picket, as at 22, at that end of the section which is free of a base projection 19. The other end of the rail projects beyond the end-most picket of the section enough to stand centrally of the end-most picket of an adjacent fence section where it abuts the centrally placed end of the rail 12 of the adjacent section. The rails 12 may be nailed or otherwise secured to each picket across which they extend. I prefer, however, to secure that end of each rail 12 which is positioned centrally of a picket on its section by means of a screw 24, and to provide the opposite end of each rail with a hole 26 so that it too may be secured by a screw when the sections are combined in a fence.

The fence sections may be staked to the ground in any suitable manner, but I preferably equip each fence section with at least one stake 28 which conveniently is pivotally secured as at 30 to the base extension 19. As illustrated in Fig. 2, each stake is swingable on its pivot 30 between the dotted and full line positions shown in Fig. 2 and, when swung to its position projecting generally at right angles to the base line of the sections, a substantial portion of the stake is in position to overlap the base portion of the adjacent section, so that this latter section may be quickly secured to the stake either before or after driving of the stake. A hole 32 may be provided in each stake to facilitate the securing thereof-

to of an adjacent section by a screw or nail or any other securing means.

When the fence sections are combined to provide a straight fence, one end-most fence section will require a stake at each end thereof, and this extra stake may be similar to the stakes 28 or may be any suitable staking device secured to or securable to the section.

It is a feature of the invention that the fence sections have resilient flexibility whereby they readily may be flexed to provide arcuate, sinuous or circular fences as may be desired. In the case of a plywood panel 10, the two surface plies will have their grain running in the direction of extent of the pickets 20. This provides desired stiffness and rigidity for the pickets, which are additionally strengthened and tied together by the rails 12, and provides a desired degree of flexibility of the base portions 18 and the rails whereby the sections may be readily flexed to arcuate shape longitudinally, thereby to enable associated sections to be arranged and staked in various shapes, such as in a circle, as represented in Fig. 3.

When the fence rails 12 are cut from a plywood panel 10 having three plies of which the two outer plies have their grain extending in the direction of extent of the pickets 20, it will be obvious that the grain of the two outer plies of the rails 12 will extend crosswise of the rails. This provides great flexibility for the rails, yet the center ply introduces needed strength against breaking when the rails are flexed. Actually a four foot section of fence as herein described, with a fence rail 12 thereon, may be formed by flexing into a relatively small complete circle which may surround a bush or the like. In such a case, in addition to the post 23 at the juncture of the two ends of the section, an additional post 28 will be located at a mid-location between the ends of the section.

It will be obvious that the fence sections, each complete with attached rail and pivoted stake, conveniently and compactly may be stacked in generally flat condition with the stakes 28 swung out of projecting position. Orders for any particular length of fence quickly and conveniently may be filled by selection of the required number of fence sections. A fence easily may be installed without need for any particular skill with the aid of a hammer to drive the stakes and a screw-driver to drive two screws at each juncture of fence sections; or the sections may be secured by nails in which case only a hammer will be necessary.

While the ramoso elements as herein disclosed have a particular utility as sections of picket fences, they may be employed as racks for various purposes, and a single element in proper size may serve effectively as the toothed head of a rake as illustrated in Fig. 4 where the ramoso element 34 has a handle 36 secured thereto by a suitable bracket 38.

65 I claim as my invention:

1. A picket fence section readily combinable with other similar sections to constitute a fence, said section being the total residue of a rectangular plywood panel from which an identical fence section was removed, and comprising an intact base portion extending from end to end of the section, a multiplicity of uniformly dimensioned pickets integral with said base portion and projecting therefrom in parallelism with the space 70 between pickets equal to the width of a picket,

said base portion having one of its ends in the plane of the outer edge of one end-most picket and having its other end projected beyond the other end-most picket a distance equal to the width of a picket, a stake pivotally mounted on the said projected end of the base portion and swingable between a position where every portion thereof overlies the base portion and a position where it projects a substantial distance generally at right angles to the base edge and also projects beyond said projected end of the base portion for attachment thereto of an adjacent fence section.

2. A picket fence section readily combinable with other similar sections to constitute a fence, said section being the total residue of a rectangular plywood panel from which an identical fence section was removed, and comprising an intact base portion extending from end to end of the section, a multiplicity of uniformly dimensioned pickets integral with said base portion and projecting therefrom in parallelism with the space between pickets equal to the width of a picket, said base portion having one of its ends in the plane of the outer edge of one end-most picket and having its other end projected beyond the other end-most picket a distance equal to the width of a picket, a stake pivotally mounted on the said projected end of the base portion and swingable between a position where every portion thereof overlies the base portion and a position where it projects a substantial distance generally at right angles to the base edge and also projects

beyond said projected end of the base portion for attachment thereto of an adjacent fence section, and a rail strip having one end secured to the end-most picket whose outer edge is in the plane of an end of the base portion with the end of the strip on the center-line of the picket, said rail strip extending thence right-angularly across all of the other pickets and projecting beyond the other end-most picket a distance equal to one and one-half times the width of a picket whereby it extends to the center-line of the end-most picket of an adjacent fence section, said rail strip being secured to each picket of the section.

BOARDMAN M. RANDALL.
